SPOT-TIE CUTTER OR SIMILAR ARTICLE

Lewis P. David, Norwalk, Calif., assignor to
North American Rockwell Corporation

Filed Oct. 20, 1969, Ser. No. 19,619

Term of patent 14 years

Int. Cl. D8—02

U.S. Cl. D8—58

FIG. 1

FIG. 2

FIG. 3

FIG. 4

FIG. 1 is a perspective view of a spot-tie cutter or similar article showing my new design;

FIG. 2 is a top plane view of the spot-tie cutter or similar article thereof;

FIG. 3 is a bottom plan view of the spot-tie cutter or similar article; and

FIG. 4 is a side elevational view of the opposite side of the spot-tie cutter or similar article not shown in FIG. 1.

I claim:

The ornamental design for a spot-tie cutter or similar article, as shown and described.
